UNITED STATES PATENT OFFICE.

OTTO MALCHER, OF CHICAGO, ILLINOIS, ASSIGNOR TO MALCHER ADDING MACHINE COMPANY, OF CHICAGO, ILLINOIS, A CORPORATION OF ILLINOIS.

CALCULATING-MACHINE.

1,318,396.

Specification of Letters Patent.

Patented Oct. 14, 1919.

Application filed March 25, 1914. Serial No. 827,049.

To all whom it may concern:

Be it known that I, OTTO MALCHER, a citizen of the United States, residing at Chicago, in the county of Cook and State of Illinois, have invented certain new and useful Improvements in Calculating-Machines, of which the following is a specification.

This invention relates to calculating machines generally and the totalizer thereof particularly, and has for its object the provision of an improved totalizer for use in connection with the calculating machine described and illustrated in my application Serial No. 825,782, filed March 19, 1914.

This totalizer is designed to embody an improved carrying mechanism of the delayed type, which is positively driven after the completion of a calculation, and wherein the number-bearing members or wheels of the totalizer are constantly trued. It is also desired to reduce the number of parts embodied in the totalizer, thereby producing a simple, positive and inexpensive totalizer. With the above and other objects in view, as will be apparent, this invention consists in the construction, combination and arrangement of parts all as hereinafter more fully described, claimed and illustrated in the accompanying drawings, wherein—

Figure 1 is a fragmentary plan view of a calculating machine illustrating in detail the totalizer forming the subject-matter of the present invention;

Fig. 2 is a transverse section taken along the line 2—2 of Fig. 1, and illustrates the coöperation and arrangement between the elements of the totalizer, particularly the carrying mechanism and the arms of the automatic clearing mechanism;

Fig. 3 is a perspective view of one of the yokes which coöperate with each denominational order of the totalizer controlling the carrying mechanisms;

Fig. 4 is a longitudinal section taken along the line 4—4 of Fig. 1, and illustrates the drive of the carrying mechanisms;

Fig. 5 is a longitudinal section taken along the line 5—5 of Fig. 1 to illustrate the details of construction of the totalizer, particularly the means for imparting the varied movement to the number-bearing members thereof and the transfer or carrying mechanisms and the operation thereof.

Fig. 6 is a fragmentary vertical sectional

view of the operating dogs for imparting motion to the driving mechanism.

The totalizer forming the subject-matter of the present invention comprises a plurality of number-bearing members or numeral wheels, which are rotatable by a plurality of reciprocal racks in either direction. The present invention provides two positively driven carrying shafts, operable in reverse directions, which carry sliding carrying gears, each shaft carrying one gear for each denominational order of the numeral wheels. These carrying gears are operable only when the calculation upon the numeral wheels has been completed, which calculation sets the carrying gears for operation. Two sets of carrying gears are provided for one totalizer, one of which co-operates with said totalizer for either direction of rotation thereof, so that when the totalizer is operating subtractingly, one set of carrying gears will coöperate therewith, and when it is operating addingly the other set of carrying gears will coöperate therewith, the rotation of the carrying gears being regulated to correspond with the rotation of the totalizer, dependent upon the calculation performed.

Referring more particularly to the drawing, 10 indicates a totalizer shaft mounted in the frame or casing of the machine, indicated generally as 11. Loosely mounted upon this totalizer shaft are a plurality of units, one unit for each denominational or decimal order. Each unit comprises a numeral wheel 12, a star wheel 13, a driving gear 14 and a ten-toothed gear 15, by means of which the carrying is accomplished. These elements, to-wit, the numeral wheel 12, the star wheel 13, the drive gear 14 and the ten-toothed gear 15, are secured together and loosely mounted upon the shaft 10 for simultaneous rotation thereon. Keyed to the totalizer shaft 10 adjacent to each numeral wheel 11 and extending upon both sides of said shaft is a normally horizontal bracket 16, which carries a gear 17. This gear 17 is arranged to mesh with one side or the other of the double reciprocal rack 18 and at the same time constantly meshes with the drive gear 14 of the totalizer unit with which it coöperates. Assuming that the gear 17 is in mesh with one side or the other of the reciprocal rack 18, the movement of said

rack will rotate this gear 17, thereby rotating the drive gear 14, the star wheel 13, the numeral wheel 12 and the ten-toothed gear 15. Thus it will be seen that the movement 5 of the racks, which is designed to impart a variable movement to the number-bearing members, directly and positively operates the totalizer units.

- In the machine with which the totalizer 10 forming the subject-matter of the present invention is arranged to coöperate, a primary drive shaft 19 is provided, which is arranged to rotate a quarter of a revolution in the direction of the arrow X in Fig. 4, 15 at each calculation of the machine. A collar or sleeve 20 is loosely mounted upon this primary drive shaft and carries at its inner terminal a large gear 21, which is arranged to mesh with and drive a gear 22 mounted 20 upon and keyed to the secondary drive shaft 23, which rests in the same horizontal plane as the primary drive shaft 19. By the provision of the pawls 24 and 24^a, Figs. 1 and 6, the primary drive shaft 19 is rotated a 25 quarter of a revolution in the direction of the arrow X in Fig. 4, and at the completion of that movement the operating crank or handle 25 is released, which causes the sleeve 20 to take a quarter of a revolution in the 30 reverse direction to the arrow X, Fig. 4. The operation of the parts 19 and 20 is produced by the pawls 24 and 24^a carried by the projection 25^a on the crank 25. The pawls 24 and 24^a coöperate with ratchet 35 wheels 19' and 20' connected with shaft 19 and sleeve 20 respectively. As the secondary drive shaft 23 is geared to the sleeve 20 at a ratio of 4 to 1, it will be rotated a complete revolution. The secondary drive shaft 23 40 operates the printing mechanism and restores the various operating parts of the machine not forming a part of this invention. It is during the forward quarter cycle movement of the primary drive shaft 19 that the 45 racks 18 are released to reciprocate forwardly to rotate the drive gears 14 through the medium of the movable gears 17, thus registering a number or item upon the totalizer.
- 50 In the totalizer forming the subject-matter of the present invention, the carrying operation is accomplished after the completion of the movement of the primary drive shaft 19 and during the operation of the secondary 55 drive shaft 23, the carrying gears, however, being set during the movement of the primary drive shaft 19; that is to say, during the calculation.

Upon each side of the totalizer shaft 10 60 and arranged parallel thereto and in the same horizontal plane, are the carrying shafts 26 and 27. The carrying shaft 26 has a gear 28 keyed thereto which meshes with the large gear 21 carried by the sleeve 20 65 mounted upon the primary drive shaft 19.

This rotates the shaft 26 in the same direction as the primary drive shaft 19 and in the opposite direction to the direction of rotation of the gear 21. The carrying shaft 27 has a gear 29 keyed thereto, which meshes 70 with a wide gear 30 loosely mounted upon the automatic clearing shaft 31. One side of this wide gear 30 meshes with the gear 29, while the opposite side thereof meshes with the gear 21. By this arrangement, the carrying shaft 27 rotates in the same direction as the primary drive shaft 19 and in the opposite direction to the sleeve 20 and the large gear 21 carried thereby, and also in a direction opposite to that of the carrying 80 shaft 26.

The carrying shaft 26 is arranged to coöperate with the totalizer when said totalizer is operating subtractingly, while the carrying shaft 27 is adapted to coöperate 85 with the totalizer when said totalizer is operating addingly. Mounted on each carrying shaft 26, 27 and keyed thereto for reciprocation are a series of one-toothed gears 32, which are staggeredly arranged upon 90 their coöperating shaft so that said gears will coöperate with the units of the totalizer successively. One side of each gear 32 is operated upon by a spring 33, which is interposed between the rack 18 of the coöperating totalizer unit and the body of the gear, and encircles its carrying shaft. The action of this spring is such that if the coöperating carrying gear were not held from movement, as will be hereinafter apparent, 95 the spring would force the carrying gear 32 toward the opposite rack 18 to that against which the spring bears along the shaft until said carrying gear was alined with the ten-toothed gear 15 of the coöperating totalizer 100 unit. It is apparent that as the shafts 26 and 27 are positively driven from the source of power after the calculation, all of the carrying gears 32 alined with their coöperating ten-toothed gears 15 will impart a step 110 of rotation to the ten-toothed gears 15, thereby inserting "1" upon the units of the totalizer with which they coöperate.

The opposite surface of each carrying gear 32 is provided with a projection 34 115 and a collar 35, which are formed integral therewith or otherwise secured. The collar 35 is provided with a cam surface 36, which, as will be seen from Fig. 5, is arranged in close proximity to the tooth of the coöperating gear 32 and is arranged to follow said tooth. This cam surface is provided for returning the gear 32 to its inoperative and normal position, and its arrangement with respect to the tooth of its coöperating gear 120 is such that the return of the gear occurs immediately after the meshing of the tooth thereof with the coöperating ten-toothed gear 15. The ten-toothed gear 15 of each unit of the totalizer is provided with a pin 125 130

37, projecting therefrom at a position equivalent to the position of the digit 9 on the coöperating numeral wheel 12 when said digit 9 is at or adjacent to the reading line.

5 Loosely mounted upon the primary drive shaft 19 and under each unit of the totalizer, is a yoke 38, which carries two fingers 39 extending vertically in the plane of the yoke, and an offset finger 40. A spring 41 is connected to the under side of each yoke 38 and to a stationary part 42 of the machine, said spring acting upon said yoke to hold the same in a normally vertical position. The offset arm 40 of each yoke coöperates 10 with the pin 37 of one unit of the totalizer, while the fingers 39, 39 thereof coöperate with the carrying gears 32 of the unit of the totalizer of the next higher order, as illustrated in Figs. 2 and 5, said fingers 39, 39 bearing against and engaging the projections 34 of said carrying gears. That is to say, if the finger 40 is engaged by the pin 37 of the ten-toothed gear 15 of the 15 unit of the totalizer corresponding to the units denominational order, the fingers 39, 39 thereof will coöperate with the carrying gears 32 of the unit of the totalizer representing the tens denominational order, so that when the gear 15 of the units denominational order contacts with the arm 40 through the medium of the pin 37 and oscillates the yoke 38 against the tension of the spring 41, one or the other of the fingers 39 will release its coöperating carrying gear 20 32 of the tens denominational order to align the same with the ten-toothed gear 15 of said tens denominational order; and hence, when the carrying shafts are rotated after the completion of the calculation, one digit 25 will be inserted on or subtracted from the tens numeral wheel by the meshing of the carrying gear 32 with the ten-toothed gear 15, dependent upon the calculation and direction of rotation of the numeral wheels.

30 40 The rotation of the numeral wheel and its coöperating elements, including the ten-toothed gear 15 carrying the pin 37, will cause said pin 37 to contact with one side or the other of the finger 40 of the coöperating yoke 38. If the pin 37 coöperates with one side of the offset finger 40, one of the gears 32 upon one of the carrying shafts will be released, while if the pin 37 contacts with the opposite side of the offset finger 45 40, the opposite gear of the opposite carrying shaft is released. Thus, the carrying gears which coöperate with the totalizer are regulated and controlled by the direction of rotation of the totalizer, so that the carrying 50 or the insertion of the extra digits will be accomplished to correspond to the direction of rotation of the totalizer.

Immediately after the tooth of each carrying gear 32 meshes with its coöperating ten-toothed gear 15, the cam surface 36 thereof

will contact with the adjacent terminal of the bracket 16 of the next adjacent unit of the totalizer, which causes the gear 32 to be returned to its initial position and engaged by the coöperating finger 39 as the cam surface passes over the adjacent terminal of the bracket 16, which causes the gear to reciprocate on its shaft. It is therefore apparent that the teeth of the carrying gears 32 not only contact with their coöperating ten-toothed gears 15 successively, but that they are returned to their normal and inactive positions successively, immediately after the insertion of the extra digit.

The automatic clearing shaft 31 has a plurality of dogs 42 loosely mounted thereon, the terminals of which are arranged to enter between the teeth of the star wheels 13 to constantly keep each unit of the totalizer trued and to take up such lost motion as may occur in the totalizer. The outer ends of the dogs 42 are acted upon by the springs 43, which extend and are secured to the collars 44 loosely mounted upon the secondary drive shaft 23.

The automatic clearing shaft 31 also carries a plurality of clearing arms 45, which at their terminals are provided with the teeth 46 for engagement with the pins 37 of the aligned ten-toothed gears 15. These arms 45 are keyed to the shaft 31, and when said shaft is oscillated are arranged to have their teeth 46 projected into the paths of movement of the pins referred to. The shaft 31 is provided at its terminal with the dependent arm 47, which is pivoted to the slide 48. This slide is operated by the "auto clear" key 49. When the slide 48 is reciprocated, the shaft 31 is oscillated, bringing the teeth 46 of the arms 45 into the paths of movement of the pins 37. If the totalizer is operated addingly, the clearing thereof is accomplished by reversing its direction of rotation, which causes the totalizer to operate subtractingly. Thus, when the shaft 31 is oscillated to locate the arms 45 as described, the pins 37 contact with the teeth 46 to limit the rotation of the numeral wheels 12 and exhibit a series of zeros at the sight line. If the totalizer is operating subtractingly, no change is made in the direction of rotation thereof, the shaft 31 being merely oscillated to position the arms.

In this totalizer, the numbers to be registered are first set up on the keyboard (not shown), which acts as a stop for the racks 18, which operate the totalizer. The crank 25 is then pulled forwardly, which imparts a quarter of a cycle rotation to the primary drive shaft 19. Previous to pulling the crank 25, however, the shaft 50 is set to operate the mechanism 51 to determine the character of the calculation. The mechanism for setting the totalizer for adding and subtracting is not a part of the present inven-

tion and it is sufficient to say that it shifts the shaft 10 to bring the totalizer into operative relation with the upper or lower teeth of the racks 18 during the movement 5 of these racks, the upper teeth operating the totalizer in one direction and the lower teeth in the other. During the first portion of movement of the primary drive shaft 19, the totalizer shaft 10 through the medium of the 10 mechanism 51, is oscillated to bring the gears 17 carried by the bracket 16 into mesh with one side or the other of the coöperating racks 18, which determines the direction of rotation of the totalizer.

15 The crank is then released and is returned to its normal, inactive position, under the influence of the spring 52, which causes the gear 21 to rotate, imparting such rotation to the secondary drive shaft 23 and to the 20 carrying shafts 26, 27, both of which are positively rotated in opposite directions. If during the calculation it is necessary to perform any carrying, the yokes 38 are oscillated through the medium of the offset 25 fingers 40 coöperating with the pins 37 of the ten-toothed gears 15, which sets the proper carrying gears 32, dependent, of course, upon the direction of rotation of the units of the totalizer. Consequently, when 30 the carrying shafts 26 and 27 are positively rotated from the gear 21, all of the carrying gears 32 carried thereby will be rotated, and those which are set to coöperate with the ten-toothed gears 15 will mesh with said ten-toothed gears 15, inserting one digit on the 35 numeral wheels rotating with such ten-toothed gears 15, and are instantly returned to their normal and inactive positions for engagement with the coöperating fingers 39 by 40 the cam surfaces 36 thereof, contacting with the adjacent terminals of the brackets 16.

What is claimed is:

1. In a totalizer, the combination with a 45 plurality of numeral wheels, of a plurality of separately mounted sets of carrying mechanisms to coöperate therewith, and means for causing the carrying mechanisms of said sets to coöperate alternatively with said numeral wheels.

2. The combination with a series of coaxial numeral wheels, of a plurality of separately mounted carrying mechanisms coöperating therewith, and means for selectively 55 operating either of said carrying mechanisms to successively carry from one numeral wheel to another after the completion of a calculation.

3. The combination with a plurality of 60 reversible numeral wheels, of two carrying shafts operating in opposite directions, and carrying gears arranged on each of said shafts for coöperation with the numeral wheels.

65 4. The combination with a plurality of re-

versible numeral wheels, of means for operating said numeral wheels in either direction, two carrying shafts, means for rotating said carrying shafts in opposite directions and means governed by the rotation of said 70 numeral wheels for controlling the connection between said carrying shafts and numeral wheels.

5. The combination with a plurality of 75 reversible numeral wheels, of means for operating said numeral wheels in either direction, a pair of carrying shafts, means for operating said carrying shafts in opposite directions so that each of said shafts corresponds to one of the directions of rotation 80 of the numeral wheels, and means for connecting said numeral wheels with one of said shafts for one direction of rotation of said wheels and with the other of said shafts for the other direction of rotation of said 85 wheels.

6. The combination with a plurality of 90 reversible numeral wheels, of a pair of oppositely driven carrying shafts, carrying gears mounted for reciprocation thereon, means for setting the gears of one shaft to coöperate with the numeral wheels for one direction of rotation of said wheels and for setting the gears of another shaft for co-operation with said numeral wheels for the 95 other direction of rotation of said wheels.

7. The combination with a plurality of 100 reversible numeral wheels, of a pair of carrying shafts, means for operating said carrying shafts in opposite directions, movable carrying gears mounted on each shaft, means for setting the gears of one or the other of the shafts to coöperate with the numeral wheels to correspond to the direction of rotation thereof and subsequent to the calculation, and means controlled by the rotation of said numeral wheels for reciprocating said gears on said shaft to connect the said gears with said numeral wheels.

8. The combination with a plurality of 110 reversible numeral wheels, of a pair of carrying shafts coöperating therewith and operable in reverse directions, a set of carrying gears mounted on each shaft, and means coöperating with each numeral wheel whereby 115 one or the other set of carrying gears may coöperate with the numeral wheels.

9. The combination with a plurality of 120 reversible numeral wheels, of a separately mounted individual carrying mechanism for each direction of rotation of the numeral wheels, and means for operating said carrying mechanisms.

10. The combination with a plurality of 125 reversible numeral wheels, of means for operating said numeral wheels, two oppositely rotated carrying shafts, means for operating said shafts subsequently to the operation of the numeral wheels, and carrying gears mounted on said carrying shafts,

11. The combination with a plurality of co-axial numeral wheels, of a gear arranged adjacent to each numeral wheel and arranged to rotate therewith, a series of co-axial carrying gears, one gear for each numeral wheel, said gears having a common drive separate from the operating mechanism of said numeral wheels and upon which the gears are mounted for reciprocation, and means controlled by the gear of one numeral wheel for setting the carrying gear aforesaid for registering with the gear of the numeral wheel of the next higher denominational order.
12. The combination with a plurality of co-axial numeral wheels, of a gear co-operating with each numeral wheel and arranged to rotate therewith, a series of co-axial reciprocable carrying gears, one for each numeral wheel, a common drive shaft for said carrying gears on which said gears are mounted, means for retaining the carrying gears in their inoperative position, and means operable from the gear of each numeral wheel to set the carrying gear for co-operation with the gear of the numeral wheel of the next higher denominational order.

13. In a totalizer, a plurality of numeral wheels, two sets of oppositely rotating carrying devices for said numeral wheels, and mechanism operating according to the direction of rotation of said numeral wheels for bringing the carrying devices of one or the other of said sets into operative relation with said numeral wheels.

14. In a totalizer, a plurality of co-axial numeral wheels, a pair of oppositely rotating carrying shafts for said wheels, carrying gears on said shafts, and mechanism for automatically causing the gears of one shaft to co-operate with said numeral wheels when said numeral wheels are rotated in one direction and the gears of the other of said shafts to co-operate with said numeral wheels when said wheels are rotated in the opposite direction.

In testimony whereof I have signed my name to this specification, in the presence of two subscribing witnesses, on this 23rd day of March, A. D. 1914.

OTTO MALCHER.
